(57) **CLAIM**

The ornamental design for a clasp for a wearable physiological monitor, as shown and described.

DESCRIPTION

FIG. 1 is a top perspective view of a clasp for a wearable physiological monitor;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a right side view thereof, shown in a first open position to demonstrate movement of the moveable clasp;

FIG. 9 is a right side view thereof, shown in a second open position to demonstrate movement of the moveable clasp;

FIG. 10 is a right side view thereof, shown in a third open position to demonstrate movement of the moveable clasp;

FIG. 11 is a top-front perspective view thereof, shown in an environment of use; and,

FIG. 12 is a top-rear perspective view thereof, shown in an environment of use.

The broken lines showing portions of the clasp for a wearable physiological monitor show portions of the article that form no part of the claimed design. The broken lines showing the strap in FIGS. 11 and 12 represent environmental subject matter only and form no part of the claimed design.
